UNITED STATES PATENT OFFICE.

HAMILTON T. HOWELL, OF NEW YORK, N. Y., ASSIGNOR TO ALFRED VESTER SONS, INC., OF PROVIDENCE, RHODE ISLAND, A CORPORATION OF RHODE ISLAND.

DESIGN FOR AN ORNAMENT FOR LIGHTING-FIXTURES.

59,478.

Specification for Design.

Patented Oct. 25, 1921.

Application filed December 20, 1920. Serial No. 432,117. Term of patent 14 years.

To all whom it may concern:

Be it known that I, HAMILTON T. HOWELL, a citizen of the United States, and residing at New York, in the county of New York and State of New York, have invented a certain new, original, and ornamental Design for an Ornament for Lighting-Fixtures, of which the following is a specification, reference being had to the accompanying drawing, forming part thereof.

Figure 1, is a perspective view of a husk for lighting fixtures embodying my new design.

Fig. 2 is a front view of the same.

I claim:

The ornamental design for an ornament for lighting fixtures, as shown.

HAMILTON T. HOWELL.
